CLAIM

The ornamental design for a gun sighting rest, as shown and described.

DESCRIPTION

FIG. 1 is a perspective view of a gun sighting rest showing our new design;

FIG. 2 is a perspective view comparable to FIG. 1 except on an enlarged scale;

FIG. 3 is a side elevational view thereof, the other side being a mirror opposite;

FIG. 4 is an end elevational view thereof with the barrel-end in the foreground;

FIG. 5 is an end elevational view thereof with the trigger-end in the foreground;

FIG. 6 is a top plan view of FIG. 3;

FIG. 7 is a bottom plan view of FIG. 3;

FIG. 8 is a perspective view comparable to FIG. 2 except showing the gun sighting rest rocked up; and,

FIG. 9 is a side elevational view of FIG. 8.

The broken lines in the drawing represent environmental subject matter that forms no part of the claimed design.
